UNITED STATES PATENT OFFICE.

JOHN OTTO HEINZE, JR., OF LOWELL, MASSACHUSETTS.

INTERNAL-COMBUSTION ENGINE.

Specification of Letters Patent. Patented Dec. 14, 1909.

943,408.

Application filed July 16, 1908. Serial No. 443,755.

To all whom it may concern:

Be it known that I, JOHN OTTO HEINZE, Jr., a citizen of the United States, residing at Lowell, in the county of Middlesex and State of Massachusetts, have invented certain new and useful Improvements in Internal-Combustion Engines, of which the following is a specification, reference being had therein to the accompanying drawing.

10 My invention relates to internal combustion engines having one or more cylinders. Its principal objects and the methods of attaining them may be generally described as follows:—

15 I. That the multi-cylinders of an internal combustion engine may be kept at a substantially uniform temperature; it has been the practice, heretofore, to try to supply an equal amount of cooling water to each cylinder, or to be more specific, to its water jacket, by arranging the water piping and jackets in multiple; that is, the feed water pipe and the discharge water pipe have been tapped opposite each cylinder and connected 20 to its respective water jacket. But it has been found that often less water flows through one cylinder than through another, as because of a flaw or a fin concealed within the water jacket casting and obstructing the 25 flow of cooling water through said jacket, consequently, when such is the case, such cylinder receives less water than any of the others, radiates less heat, and remains hotter. Consequently all of the cylinders, when used, 30 do not have a substantially uniform temperature, and hence a uniformity of action. Now I attain this substantially uniform temperature by arranging the cylinders in series, and having all of the cooling water 35 successively pass through water passages in the cylinders, in one direction, and then return through other water passages in said cylinders, in an opposite direction. By so doing, the cooling water passing the first 40 cylinder in one direction is cool, but warm when returning in the opposite direction; less cool and less warm, in passing and returning by the second cylinder; still less cool and less warm, by the third cylinder; 45 and so on; the result being, that the average temperature of the cooling water passing each cylinder is substantially the same; and the same number of heat units are abstracted 50 from each of the cylinders, the temperatures 55 of which are uniform. And further should there be an obstruction in any of the water

passages in one cylinder, this obstruction will regulate the flow of all of the water through all of the water passages in the cylinders, arranged in series. In fine, all of 60 the cylinders will be supplied with the same amount of water, and will have the same uniform temperature, which, however, will vary with the amount of water supplied.

II. It is the usual practice to have the 65 water pipes and the gas pipes lead along the outside of, and connected with, each of the cylinders; the number of connections increasing in proportion to the number of cylinders. Such arrangements and connec- 70 tions are complex and expensive, and in case of assembling or dismantling the cylinders, take much time, and will involve trouble and the consequent expense. I do away with such practice by so casting each cylinder 75 that it is provided with suitable water passages, or gas passages, or both, extending through it; and then by assembling two or more of the finished cylinders in series so that they abut, and their respective passages 80 are in alinement. Whether one or more cylinders are used, there are required only a water inlet, a water outlet, a gas inlet and a gas outlet. Such pipe connections here- 85 tofore required for each additional cylinder are thus done away with. By casting each cylinder in the form hereinafter to be described, the entire exterior surface of the cylinder in the water cooling passages is exposed, and defects in the casting may be 90 easily detected.

III. In prior internal combustion engines, the circumferential valve area of the gas intake opening, and the circumferential area of the exhaust valve have not been as large 95 as desired, for the reason that large valves do not seat themselves properly, and are easily warped out of shape because of the amount of power required to open them; the larger the valve, the more power re- 100 quired, and the greater consequent strain on the cam rods and cams. To attain the increased circumferential opening area, and not to increase the amount of power necessary to lift the valves, I provide a group of 105 two or more valves controlling two or more openings having the total circumferential area desired; and means to open one of said valves slightly before the others; the area of said valve being such that the back pres- 110 sure acting against it, can be overcome by the desired amount of power, and be released

by the first valve, and so reduced that the remaining valves may be opened at the reduced back pressure. In other words, with a fixed amount of power and back pressure, 5 two or more valves having the desired total circumferential area may be opened, provided one and then the others are opened in succession, but in substance simultaneously. This feature is claimed in divisional application, Serial No. 492,505, filed by me April 10 27, 1909.

Having pointed out the general objects and the way I attain them, I will now describe the construction and operation of the 15 best forms now known to me of embodying the principles of my invention. Some minor objects and the methods of accomplishing them will become plain hereinafter.

In the drawings illustrating my invention, 20 Figure 1 is an isometric view of a series of two or more of my unit cylinders of an internal combustion engine, and the valve mechanism I employ, all mounted upon a crank case. Fig. 2 is a perspective view of a 25 molding pattern of a unit cylinder, and shows water passages and gas passages passing through the same. Figs. 3 and 4 are like views showing the interior faces of end caps which close the gas passages and connect the water passage passing through one 30 or more unit cylinders, making up the complete engine. Fig. 5 is a vertical longitudinal section showing one unit cylinder of a four cylinder engine, the crank shaft, piston, 35 valve gear and cam shaft, together with radiator, fan, feed and water pump, and water inlet and outlet in end cap of the unit cylinder. Fig. 6 is a vertical transverse section of a unit cylinder showing the water 40 passages and gas passages passing through a cylinder or cylinders; also the gas valves and their operating cams. Fig. 7 illustrates the closed position of intake group of valves; and Figs. 8 and 9 respectively show 45 in section, the pressure releasing, and the open positions of a group of outlet gas valves; the differences in the lengths of the valve stems, and their consequent movements, being somewhat exaggerated for the sake of clearness. Fig. 10 shows in plan in 50 longitudinal section, the bottom of the gas explosion chamber in each of the cylinders of a four cylinder engine; the gas inlet passage and the gas outlet passage extending through the cylinder units, being shown in dotted lines, and the course of the gas being indicated by arrows. Fig. 11 shows in 55 sectional elevation the cooling water passages outside of the cylinders; the course taken by the cooling water, through them, being shown by arrows. Fig. 12 is a diagram to illustrate the changes in the temperature of the cooling water as it passes through the water passage of a multicylinder engine.

A unit cylinder 1 is cast in iron, in one piece, the general shape of which is shown in Fig. 2. It consists of a piston cylinder 2, open at the bottom and adapted to be fixed to the top of a crank case 3, Fig. 1. It has a head 4, Fig. 1, which is rectangular in plan, and surrounds the upper portion of the piston cylinder. Extending horizontally through this head and parallel with two of its opposite sides, are two gas passages 5, 6, and water passages 7, 8, 9. Of the latter, there are three, one above another; the two lower passages 8, 9, surrounding the sides of the piston cylinder 2, while the uppermost or third passage 7 has its bottom formed by the top of the piston cylinder. The gas passages 5, 6, lie underneath the outer edge portion of an explosion chamber 10 in the cylinder head 4, Fig. 6. When more than one unit cylinder is to be used, they, as 1, 1', 1'', 1''', are mounted in series, as shown in Figs. 1, 10, 11, and secured to the top of the crank case 3, made preferably of aluminum, and supported, as by arms 11; the adjacent faces 12, 12', 12'', 12''' of the heads 4, 4', 4'', 4''' and the open ends of the gas passages 5, 6 and the water passages 7, 8, 9, all abutting and being bound together by suitable tie rods 13, 13', extending through all of the cylinder castings, Figs. 1, 6. As a consequence of this construction, there are formed water 95 passages and gas passages, common to the multi-unit cylinders. To the two open end portions of the outer cylinders, as 1, 1''', are fixed two caps 14, 15; cap 14 at one end closing the two gas passages 5, 6, and connecting the lower water passage 9 with the two upper return passages 7, 8; while cap 15 at the other, closes the opposite ends of the gas passages 5, 6, and separates the single incoming water 100 passage 9 from the two return passages 7, 8; there being in this latter cap, an inlet 16 and an outlet 17 through which cooling 105 water enters and leaves its passage.

Having now, in a general way, described 110 the form of the unit cylinder, and its gas passages and water passages, and how unit cylinders and their passages may be combined into a multi-unit cylinder engine, I will next consider, in particular, the gas passages, and the valve mechanism controlling the flow of gases through the inlet openings, and the exhaust openings, having in mind, Figs. 5 to 115 10 inclusive. A crank shaft 18 is mounted in suitable bearings 19 in the crank case 3, and is driven, in the usual way, by pistons 20, acting through the connecting rods 20'. Also extending through, and mounted in bearings in, the crank case, are two valve cam shafts 21, 22, parallel with the shaft, and driven from a gear wheel 23 on the latter, which meshes directly with two gears 24, 25, one on each cam shaft 21, 22. Upon these cam shafts are mounted the usual cams 26, 26', Figs. 6, 7, 8, 9, for operating the 120 125 130

valve mechanisms for each cylinder. A main gas feed pipe 27 opens into the inlet gas passage 5 extending through all of the castings of the unit cylinders, Figs. 6, 10; and a group of three inlet valve openings 28, 29, lead upward from the gas passage 5 into an explosion chamber 10 of each cylinder. Directly over each valve opening, and in the roof of the explosion chamber, is a threaded hole, as 30, Figs. 1, 6, through which an inlet valve, as 31 and stem 32 may be dropped into operative position, in its valve seat in its respective valve opening, the stem 32 passing down through a long bearing formed by a hole through an enlargement 33, in the wall of the gas passage; the lower end portions of stems 32, 34, Figs. 1, 6, 7 of each group, lying below the gas passage 5 and exposed to view outside of their cylinder casting. Into one of these openings for each cylinder, may be mounted a spark plug 36, the other openings being closed by suitable screw plugs 37. Upon the exposed portion of each valve stem is mounted a coil spring 38; one end of which abuts the under side of the head 4, the other end abutting a shoulder piece 39 threaded and screwed upon a correspondingly threaded portion of the exposed valve stem. A check piece 40 abuts the shoulder and also serves, by its adjustment on the valve stem, to determine the length of the valve stem. Each group of valve stems, Figs. 1, 6, 7, is operated by a horizontal lifting bar 41 which is moved into engagement with them by a vertically reciprocating cam rod 42 fixed to said bar and movable in a bearing member 43, fixed in the top of the crank case 3; said cam rod having a roller wheel 44 at its bottom portion, engaged 40 and operated by the cam 26. A coil spring 45, on the cam rod holds the roller in constant contact with the cam. By the adjustment of the shoulder pieces 39 to the check pieces 40, the length of the valve stems may be varied as desired. In all of the groups of intake valves, the valve stems are of the same length, because these valves are opened at the same time, against a back pressure substantially that of the atmosphere. But 50 with the groups of exhaust valves working against a back pressure above that of the atmosphere, all of the valves of each group, do not open at once. That they may not so open, the length of one of the three valve stems of each group of exhaust valves, as 32', Fig. 8, which I will call the release valve stem, is such that when all of the three valves are in their seats in normal position, it is just in contact with the lifting bar 41'; 55 and the other stems 34' are slightly shorter, and are slightly distant from the lifting bar; so that when the latter is moved up by the rod 42', Fig. 8, the release valve 31' with its long stem 32' is opened first, and then the other two valves 35', Fig. 9, just afterward;

and when the bar descends, the two valves 35' close first, and the release valve 31' last. It may be said that, practically, the exhaust gas passage 6 and its main outlet 48, the exhaust openings 28', 29', and exhaust valves 70 31', 35', and the lifting bar 41' and cam shaft 22 are in number and arrangement, like the intake gas openings and valve mechanism, except that the intake valves operate simultaneously, while of the outlet valves 75 the release valve operates first.

I will now explain the operation of so much of my invention as controls the flow of the gases into and out of the explosion chamber. The piston 20, Figs. 5, 6, is assumed 80 to be in its uppermost position; the burned gases have been exhausted; the inlet valves, Figs. 6, 7, and the exhaust valves are closed. In the clearance space or explosion chamber 10, of the cylinder, there is a pressure, 85 substantially that of the atmosphere. The moment the inlet cam shaft 21 is turned in the direction indicated by the arrow, the inlet cam 26 begins to act on the vertical cam rod 42. The lifting bar 41, Figs. 6, 7, at 90 once engages the three valve stems, having the same length; the three valves open simultaneously, and there results the large circumferential inlet gas area desired, and through which, during all the intake stroke 95 of the piston, a large body of gas freely flows into the explosion chamber. The piston having reached the bottom of its stroke, it next ascends, the gas or explosive mixture is compressed and then ignited at the spark 100 plug. The piston is driven downward by the explosion, and the burned gases, when the piston is at the bottom of its stroke, are at a pressure much above that of the atmosphere and are acting upon the top surfaces of the outlet or exhaust valves. But at this moment, the exhaust cam 26', Fig. 8, is beginning to raise the lifting bar 41', and the release valve 31', having the long stem 32'. In so doing, the power required is that 105 to overcome the pressure on the top of the release valve, and the tension of the coil spring 38'. In so opening this valve, the pressure in the clearance space of the cylinder is greatly reduced; the bar next raises 110 the other valves 35', 35' with shorter stems 34', 34', against said reduced pressure, and there results a large exhaust circumferential area equal to that of the three outlet valves. The piston having reached the end of its upstroke, and the exhaust cam having permitted the springs to restore the exhaust valves to their normal positions, in their respective seats, the cycle of operations, in so far as taking and exploding the gas mixture, 115 and exhausting the burned gases, is completed, and the operated mechanism is ready to repeat the cycle. In regard to both the inlet valves and the outlet valves, I gain in 120 the volume of gas taken in and exhausted; 125

in an easy transition between high and low pressure; in saving the power required to open an old valve of equal area; and in obtaining said total increased area without increasing the diameter of the valve opening.

I will now describe so much of my invention as relates to the circulation of the cooling water. The cooling water is drawn from a radiator 70, Fig. 5, through a suitable feed pipe 71, not wholly shown, but readily understood, by a screw pump 72, mounted on a shaft 73 having a journal bearing 74 in a cup chamber 75, fixed to the end cap 14 of the first cylinder 1. Into this screw cup is led the feed pipe 71, so that a rotation of the screw draws feed water from the radiator, and forces it through the inlet 16 of the cap 14 into the water passage 9 of the unit cylinder 1, and out through the water outlet 17 in the cap, into a return pipe 76 which leads back to the radiator. A continuous circulation of cooling water is thus kept up through one or more unit cylinders, the course of which will be made plain later.

To operate this pump, two pin wheels 77, 78, and a slotted belt 79 are provided; one wheel 77 being fixed to the outer end portion of the crank shaft 18 extending out through one end of the crank case; the other pin wheel 78, on the pump shaft 73; and the slotted belt 79 operatively connecting said pin wheels. Obviously while the engine runs, the pump operates. After the water is forced as above stated, through the inlet opening 16, in the cap 14, into the broad water passage 9 of the first cylinder casting, 1, it flows, as indicated by arrows in Fig. 11, around and by each cylinder until it comes to the reversing end cap 14, which deflects it into the two upper return water passages 7, 8. One part of the returning water passes around and by the cylinders, and the other flows over the top of the cylinder, so that so much of each cylinder as serves to form the walls exposed to the hot exploded gases, has substantially all of its exterior heat radiating surfaces contacting the flow of the cooling water. The heated cooling water then leaves the water passages of the cylinders, by the outlet in the front end cap, and returns in a way already described, to the radiator, the cooling of which may be accelerated by strong air currents brought about by a fan 80, fixed on the pump shaft 73.

To repeat:—All the water pumped passes about all of the engine unit cylinders, in one direction, and then turns upon itself and flows back through and out of them, the heat radiating surfaces being so proportioned that in theory, and substantially in practice, the mean temperature of the cooling water passing through each unit, is constant, and the temperature of each cylinder is constant and equal to that of every other.

To make this fact perhaps plainer, reference may be had to Fig. 12 which shows diagrammatically the mean temperature of the cooling water, due to the double passage of the cooling water, by each cylinder. For the sake of illustration, we will assume that the temperature of each cylinder without the application of cooling water, is 260 degrees Fah.; while with the water, each is kept at 240 degrees, by abstracting an amount of heat from each cylinder equal to 20 degrees of temperature. The cooling water entering the first cylinder, 1, through the broad lower passage is at 80 degrees; when it reaches the second cylinder, 1', it has acquired heat 75 from the first cylinder, and its temperature increased by 10 degrees; that is, its temperature is 90 degrees. After passing the second cylinder, 18, its temperature is again increased 10 degrees. The water entering the 80 third cylinder 1'', has 100 degrees of temperature; and 110 degrees, when entering the fourth cylinder 1''''; while on leaving the lower passage of the last or fourth cylinder, the temperature is at 120 degrees. 85 But here, the water begins flowing back through the two upper passages, 7, 8, of the cylinders. As it leaves the fourth cylinder on its return, it is at 130 degrees; that is, the mean temperature of the water passing 90 through the last cylinder is 20 degrees, and the water has abstracted from the cylinder heat sufficient to raise the temperature of the water 20 degrees. After passing through the third cylinder, it has become heated to 100 140 degrees, so that its mean temperature is equal to one half of the sum of the temperature of the incoming cooling water, viz., 100 degrees, and that of out going water, viz., 140 degrees, which equals 120 degrees. 105 This returning water acquires 10 degrees more heat in passing through the second cylinder, and its mean temperature is evidently 120 degrees; and while said water is returning through the first cylinder, it is 110 heated 10 degrees more, so that the mean temperature of the water passing through the first cylinder is likewise 120 degrees. That is, the mean temperature of the water passing through each cylinder is 120 degrees; and with a mean temperature of 120 115 degrees, the cooling water abstracts 20 degrees of heat from each cylinder. In other words, by so arranging the water passages and their heat radiating surfaces in each cylinder, that the cooling water absorbs the same amount of heat, and has a constant mean temperature, the cylinders will have a constant common temperature.

To summarize, it is evident, that each unit cylinder is of such form that it can be easily cast, and all flaws in its surfaces easily detected; that each unit is self contained as to its gas passages and its water passages, and that any number of cylinders and the neces- 130

sary gas passages and water passages may be assembled or dismembered with great ease and speed; that the gas passages are so located that the valves and stems may be mounted or removed with facility; and the adjusting devices are very accessible; that the valve mechanism is such as to permit large gas openings; that the water passages are so designed and proportioned that the cylinders are kept at a substantially uniform temperature; that the pump, fan, and cam shafts are all compactly arranged together in relation to the driving crank shaft; and conveniently accessible; in short that an engine embodying my invention is simple in construction, arrangement of parts, and operation; is strong, light in weight, and very efficient.

Having described my invention, its objects and the principles employed in obtaining them, and desiring to protect said invention in the broadest manner legally possible, what I claim is:—

1. A group of two or more abutting cylinders for an internal combustion engine, each cylinder having therethrough suitable gas passages and cooling water passages which, when the cylinders are secured together and abut, form continuous gas passages and wa- ter passages through the group; means on one end cylinder of the group, to close each open gas passage, and means to separate the water passages; means on the other end cylinder, to close each of the open gas passages, and means to connect the openings of the water passages.

2. A group of two or more abutting cylinders for an internal combustion engine, each cylinder having suitable cooling water pas- sages, which when the cylinders are secured together and abut, form continuous water passages through the group; means on one end cylinder of the group, to separate the water passages; and means on the other end cylinder, to connect the openings of the wa-

ter passages; all designed so that cooling water may flow by the cylinders in one direction, and then turn and flow back in an opposite direction.

3. A group of two or more abutting cylin- 50 ders for an internal combustion engine, each cylinder having suitable cooling water pas- sages, which when the cylinders are secured together and abut, form continuous water passages through the group; a cap for one 55 end cylinder of the group, to separate the water passages; and a cap for the other end cylinder to connect the openings of the wa- ter passages; all designed so that cooling water may flow by the cylinders in one di- 60 rection, and then turn and flow back in an opposite direction by said cylinders.

4. A group of two or more abutting cylin- ders for an internal combustion engine, hav- 65 ing therethrough suitable gas passages and cooling water passages which, when the cylinders are secured together and abut, form continuous gas passages and water passages through the group; a cap for one end cylin- 70 der of the group to close the open gas pas- sages, and separate the water passages; and a cap for the other end cylinder to close the open gas passages and connect the openings of the water passages.

5. A unit cylinder and head, all cast in 75 one piece; said head having two parallel side surfaces, and parallel water passages and gas passages extending through said head, at right angles to said parallel side surfaces; said water passages surrounding portions of 80 said cylinder within said head, and lying between the walls of said cylinder and the gas passages.

In testimony whereof I affix my signature in presence of two witnesses.
